UNITED STATES PATENT OFFICE.

JOSEPH A. RAMSEY, OF BEATRICE, NEBRASKA, ASSIGNOR OF ONE-HALF TO
CHARLES C. FARLOW, OF SAME PLACE.

CORN-HUSKER.

SPECIFICATION forming part of Letters Patent No. 645,515, dated March 13, 1900.

Application filed March 1, 1899. Serial No. 707,252. (No model.)

To all whom it may concern:

Be it known that I, JOSEPH A. RAMSEY, a citizen of the United States, residing at Beatrice, in the county of Gage and State of Nebraska, have invented a new and useful Corn-Husker, of which the following is a specification.

The invention relates to improvements in corn-huskers.

One object of the present invention is to improve the construction of corn-huskers and to provide a simple, inexpensive, and efficient device which will be strong and durable and which will permit the husk-engaging portion or hook to be readily replaced when worn.

A further object of the invention is to enable the husk-engaging hook to be readily adjusted and arranged adjacent to the thumb or the little finger or at an intermediate point to suit the size of the corn to be husked.

The invention consists in the construction and novel combination and arrangement of parts hereinafter fully described, illustrated in the accompanying drawings, and pointed out in the claims hereto appended.

In the drawings, Figure 1 is a perspective view of a corn-husker constructed in accordance with this invention. Fig. 2 is a sectional view taken longitudinally of the hook illustrating the manner of adjustably mounting the same. Fig. 3 is a detail perspective view of the supporting-plate. Fig. 4 is a similar view of the locking-plate. Fig. 5 is a perspective view of a portion of a corn-husker, illustrating a modification of the invention. Fig. 6 is a sectional view of the same. Fig. 7 is a perspective view showing the device applied to a hand.

Like numerals of reference designate corresponding parts in all the figures of the drawings.

1 designates a metal supporting-plate adapted to be arranged on the palm of the hand of the operator and curved to conform to the configuration of the same and the adjacent portion of the wrist and having its ends riveted or otherwise secured to front and rear straps 2 and 3, arranged at right angles to the plate, as clearly shown in Fig. 1 of the accompanying drawings. The front or outer strap 2, which is narrow, encircles the hand

of the operator, and the rear or inner strap 3 is wide, as shown, and passes around the wrist, and the strain is distributed between the hand and the wrist of the operator. The device is further supported by a curved brace or arm 4, extending from the front end of the plate, at one side thereof, and secured to the adjacent portion of the strap 2. The straps may be provided with the form of buckle shown; but any other suitable fastening devices may be provided for connecting the ends of the straps.

Mounted upon the plate 1 is a husk-engaging hook 5, having an inwardly-extending pointed bill and adapted to be adjusted laterally to arrange it adjacent to the thumb or to place it near the little finger or at an intermediate point to suit the size of the corn to be husked, the hook being arranged near the thumb for large corn and at the center for ordinary-sized corn and on a line with the little finger for small corn. The end of the shank of the hook is pivoted by a bolt 6 or other suitable fastening device, and a perforation 7 is provided at a point between its ends to receive a projection or stud 8 of a locking-plate 9, which moves with the hook and which is adapted to have its stud project through the opening 7 and engage any one of a curved series of perforations 10 of the supporting-plate, which forms the body portion of the device. The bolt is provided with a nut, and it not only forms the pivot for the hook, but it also serves to retain the projection or stud of the locking-plate in engagement with the said perforations.

In Figs. 5 and 6 is illustrated a modification of the invention, in which the hook is secured at the desired adjustment by means of a bolt 12, arranged to operate in a curved slot 13. The hook 14 is pivoted at 15 by a rivet or other suitable fastening device, and the bolt 12, which is provided with a nut, passes through a perforation of the hook and is adapted to secure the hook at any desired adjustment by the clamping action of the nut.

The invention has the following advantages: The corn-husker, which is simple and comparatively-inexpensive in construction, possesses great strength and durability, and there is nothing to wear out but the hook,

which can be readily replaced at a small cost. The plate which forms the body portion of the device conforms to the configuration of the hand, and the strain is distributed over the hand and wrist. The hook, which is pivotally mounted on the device, is adapted to swing laterally to arrange it near the thumb or the little finger or at an intermediate point to adapt it to operate on corn of different sizes.

10 The bolt which forms the pivot for the hook also operates as a clamp for detachably locking the stud or projection of the locking-plate in engagement with the shank of the hook and the body of the device, and it will permit the locking-plate to be readily removed from such engagement to adjust the hook.

Changes in the form, proportion, size, and the minor details of construction within the scope of the appended claims may be resorted 20 to without departing from the spirit or sacrificing any of the advantages of this invention.

What is claimed is—

1. A corn-husker comprising the trans-
versely-disposed straps arranged to encircle
25 the palm and the wrist of the operator, the
plate or body connecting the straps, the curved
arm 4 mounted on the palm-strap and con-

nected with the plate or body and arranged to extend over the upper edge of the hand, 30 and the hook adjustably mounted on the rear portion of the plate or body and adapted to be adjusted toward or from the thumb of the operator, substantially as described.

2. A corn-husker comprising the trans- 35
versely-disposed palm and wrist straps, the
longitudinal plate or body connected with
said straps and provided with a curved se-
ries of perforations, the adjustable hook piv-
oted at the rear end of the shank and pro- 40
vided with a perforation and adapted to be
moved toward and from the thumb of the op-
erator, the locking-plate mounted at its rear
end on the pivot of the hook and provided
at its front end with a stud arranged to en- 45
gage the perforations of the hook and the
plate or body, and a nut mounted on the pivot
and securing the locking-plate in its adjust-
ment, substantially as described.

In testimony that I claim the foregoing as 50
my own I have hereto affixed my signature in
the presence of two witnesses.

JOSEPH A. RAMSEY.
